UNITED STATES PATENT OFFICE

HAROLD W. DONNELL, OF NEW YORK, N. Y.

INDEX OR FILING CARD

Application filed March 10, 1930. Serial No. 434,753.

This invention relates to index or filing cards and has particular reference to a transparent attachment thereto for receiving and supporting the usual insert indicia 5 bearing tab in display position.

The primary object of the invention resides in a transparent shield or protector for index cards which facilitates the easy insertion or removal of the insert tab into display 10 position and which prevents accidental shifting of the insert tab so that the index indicia thereon is always held in proper display position.

Another object of the invention is to provide a celluloid member of substantially inverted U-shape in cross section for fitting over the finger tab of an index card, the side walls of the member being offset so as to be disposed in spaced relation to opposite 20 sides of the finger tab when the member is in position upon the index card to enable the free insertion of a folded insert tab into a straddling position relative to the finger tab.

25 A further object is to provide a celluloid index tab protector having the above mentioned features which may be cut into shape and attached to an index card at no greater cost than the present method employed.

30 With these and other objects in view, the invention resides in certain novel construction, combination and arrangement of parts, the essential features of which are herein-after fully described, are particularly 35 pointed out in the appended claims, and are illustrated in the accompanying drawings, in which:

Figure 1 is a perspective view of an index card provided with my index tab 40 protector.

Figure 2 is an enlarged vertical transverse sectional view on the line 2—2 of Figure 1.

Figure 3 is a fragmentary perspective 45 view showing the celluloid protector in a separated position with respect to the index card.

Figure 4 is a sectional perspective view showing the same principle applied to a 50 different form of index card.

Figure 5 is an enlarged vertical transverse sectional view on the line 5—5 of Figure 4.

Referring to the drawings by reference characters, the numeral 10 designates an index card of the usual well known construction, and which is provided with a finger tab 11 extending from the top edge thereof. Fitting over the finger tab 11 is my improved transparent tab protector 12 which is constructed of a single piece of transparent celluloid, bent midway between its ends to provide a substantially inverted U-shaped body 13. The opposite side walls of the body 13 are outwardly offset as at 14, the free ends of the body beyond the offset portion 14 being wider than the portions of the side walls from the offset portions 14 to the right portion of the body and which enlarged portions constitute attaching wings 15. 55

The substantially inverted U-shaped body member 13 fits over the finger tab 11 so that the attaching wings 15 embrace opposite sides of the index card 10, the transversely disposed offset portions 14—14 being disposed on a plane flush with the top edge of the index card as illustrated in Figure 1. The inner faces of the attaching wings 15 or the opposite sides of the card 10 adjacent 75 the finger-piece 11 may be provided with an adhesive for facilitating the retaining of the transparent protector to the index card. When the transparent protector is in an attached position, the upper offset walls 16—16 are disposed in spaced relation to 80

opposite sides of the finger tab 11 to provide spaces for the insertion of the folded inset tab 17, the folded sides of which straddle or embrace opposite sides of the finger tab 11. It is of course understood that the insert tab 17 is provided with the desired index indicia and may be inserted and removed when desired. The opposite edges of the right portion of the protector member are cut inwardly as at 18 to expose 85 opposite ends of the insert tab 17 to enable grasping of the tab when it is desired to remove the same from the index card for the purpose of changing the index indicia. 90 100

From the foregoing description, it will be seen that the spaces provided intermediate opposite sides of the finger tab 11 and the adjacent walls 16-16 of the protector facilitates the easy insertion of the index insert tab 17 without necessitating the forcing of the same therein and which is an objection to the present construction of celluloid protector, as the face now provided between the protector and the index card necessitates forcing of the insert tab and accidental bending of the same during insertion.

In Figures 4 and 5 of the drawings I have illustrated the same principle applied to the well-known type of index attaching strip 19, and for this purpose the protector is constructed of a length equal to the length of the strip 19. In this form of the invention, the celluloid protecting strip is indicated in its entirety by the reference character 12' and which is substantially of inverted U-shape in cross section, the opposed side walls of the same being offset as at 14' to permit of the insertion of the insert strip 17 in straddling position relative to opposite sides of the index-attaching strip 19. The same features afforded by my improvement set forth in the preferred form applies equally to the modified form, and a further description of the modification is not deemed necessary.

While I have shown and described what I consider to be the preferred embodiment of my invention, it will be understood that many of the details may be varied if desired without departing from the spirit of the invention and I do not wish to limit myself to anything less than the whole of my invention limited only by the appended claims.

Having thus described the invention, what I claim as new and desire to secure by Letters Patent is:—

1. In combination with an index card having a finger tab extending from one of the edges thereof, a protector member constructed of a single piece of bendable transparent material and being of substantially inverted U-shape in cross-section fitting over said finger tab and down against opposite sides of said index card, the opposed side walls of said protector member being outwardly offset on a plane above the adjacent edge of said index card and adhesively secured there-to below said edge, while the portions of the opposed side walls and bight portion of the said member above the adjacent edge of said card are disposed in spaced relation with respect to the opposite sides of said finger tab to facilitate the free insertion of a double index tab therebetween.

2. In combination with an index card or sheet having a finger tab integral therewith and extending from one of the edges thereof, a protector member constructed of a

single piece of bendable transparent material bent mid-way between its ends into substantially inverted U-shape in cross section, the side walls of said member fitting over said finger tab with the bight portion of the member in spaced relation to the top edge of said finger tab and its side walls embracing opposite sides of said card or sheet, the side walls of said member on a plane above the top edge of said card or sheet being outwardly offset with respect to the portion of the side walls embracing said card or sheet to provide spaces on opposite sides of said finger tab, there being an adhesive bond between said card or sheet and the side walls of said member, the bight portion of said member being cut away at opposite sides to expose the end folded edges of a folded insert tab of a length equal to the length of said member when inserted into said member with the fold portions straddling said finger tab.

In testimony whereof I affix my signature.

HAROLD W. DONNELL.
